WELL PERFORATOR

Louis D. Barber, Burbank, Calif.

Application January 24, 1948, Serial No. 4,185

6 Claims. (Cl. 164—0.3)

1

My invention relates generally to perforating or piercing devices and particularly to a device for perforating tubular elements such as well casings.

During the drilling of relatively deep subterranean wells, it is the usual practice to drive connected sections of steel tubing or casing into the hole being drilled, the casing closely following the drill which bores a hole which is slightly larger than the casing to adapt the casing sections to be readily lowered into place. During the drilling operation, drill fluid is forced down through the casing to facilitate the cutting operation, this fluid passing upwardly on the outside of the casing and carrying with it the loosened material or cuttings to the surface of the ground. As is well known to those versed in the art of well drilling, after the well has been drilled to the required depth it is necessary to perforate the wall of the casing adjacent its lower end to permit the oil or water, as the case may be, to enter the casing, the liquid then being drawn upwardly through the casing by suitable pumps. The present invention is concerned with means for perforating the wall of the well casing and relates particularly to a perforating device of a mechanical nature, as distinguished from the so-called "gun" type perforators.

Mechanically operated casing perforators now in use include a body member which is lowered into the well casing by means of a cable attached to the upper end of the body member. Pivoted to the body member are upper and lower bell-crank levers, usually arranged in pairs, the levers of each pair supporting between them a gripping member. The bell-crank levers are operated from the surface of the ground by means of a cable connected thereto, movement of the levers in one direction causing the gripping members to move radially outward into engagement with the interior of the casing so as to lock the device within the casing during a perforating operation, and movement of the levers in the opposite direction effecting inward movement of the gripping members so as to release the device. A cutter or perforating member is pivoted on each gripping member and operated by the cable which actuates the gripping members, the arrangement being such that the gripping members first lock the device within the casing and the cutters subsequently perforate the wall of the casing.

In practice, the entire perforating device is first lowered to a point adjacent the lower end of the casing or to any other selected position and

2

the operating cable is then drawn upwardly to actuate the perforators or cutters so as to pierce the casing wall. It is desirable that a series of the perforations be made around the periphery of the casing and in an effort to produce such a group of perforations, the gripping members are released following each perforating operation and the entire device is turned within the casing to move the cutters to new angular positions, this indexing of the cutters being accomplished by merely turning the cables.

It has been determined that when such a means is employed and procedure is followed in spacing the perforations circumferentially of the casing, it is impossible to control the spacing with any degree of accuracy. This is due to the fact that the long supporting cables are apt to twist so that the position of the cutter members cannot be ascertained or controlled. As a result, it often happens that the perforations are improperly spaced and, in some instances, they are disposed so close to previously formed holes that they connect with these adjacent perforations to provide relatively large openings in the casing through which pieces of rock can pass.

It is also common practice to provide additional groups of perforations above the first or lower series of holes in the casing, the perforator being raised successively to new positions following the perforating of each series of holes. Due to the fact that the perforating device is lifted by the cable, which has considerable stretch, the exact position of the cutters is undeterminable and consequently the perforations are not made at the desired vertical locations. In other words, the perforations are quite apt to be spaced haphazardly in both horizontal and vertical directions with the result that the well casing is sometimes weakened by oversize openings which permit the entrance of stones from the earth.

It is a primary object of my invention to provide a perforating device which is especially designed to perforate well casings and which will overcome the difficulties experienced with prior devices of this general character.

Another object of the invention is to provide a perforating device which, in addition to being more efficient in perforating the well casing, can be positively located in both horizontal and vertical directions by means controlled at the surface of the ground so that the perforations can be cut at selected positions and the possibility of the perforations being cut too close to adjacent perforations to weaken the casing structure is thereby avoided.

Another object is to provide a device, of the character referred to, which includes a body member adapted to be lowered into the well casing, gripping members movable radially of the body member for gripping the wall of the casing to lock the device in selected positions, perforating members pivoted on the body member and having cutters adapted to perforate the wall of the casing when the perforating members are pivoted radially outward; and a slide member 10 slidable longitudinally of the body member for actuating the perforating members. It is also an important object of my invention to provide an improved means for actuating the slide member, this means preferably consisting of a fluid cylinder mounted on the body member and a piston slidable in the cylinder and connected to the slide member. Motive fluid introduced into the lower end of the actuating cylinder moves the slide member upwardly to operate the cutters, the fluid under pressure passing downwardly from the surface of the ground to this end of the cylinder through a rigid hydraulic line extending within the well casing. The above-mentioned hydraulic line is disposed within a second rigid line which has its lower end connected to the upper end of the actuating cylinder, there being a head or column of hydraulic fluid provided in the second line. By this construction, when the pressure is relieved within the lower end of the cylinder, the column of fluid within the second line exerts sufficient force against the top of the piston to lower the slide member and thus return the cutters to inoperative position.

In accordance with my invention, the upward flow of hydraulic fluid within the second or outer line during the actuation of the cutters may be observed by the operator above the surface of the ground and, since this flow is proportional to the sliding movement of the piston and pivotal movement of the perforating members, the amount of radial movement imparted to the perforators or cutters can be readily determined by the operator so that the possibility of actuating the cutters through a distance which is insufficient to produce a complete perforating of the casing wall is obviated, and this is another important object of my invention.

It has been stated that the fluid for actuating the hydraulic means is supplied to the cylinder through rigid tubes or lines from which the device is suspended. Such a structure is extremely important to the successful operation of my improved perforating device since it enables the device to be accurately disposed at selected locations within the well casing. Since the elongating and twisting characteristics are practically nil, it is apparent that the perforating device can be rotated to selected angular positions or raised and lowered to various vertical positions with a high degree of accuracy so that the perforations can be spaced with great precision. This constitutes an important improvement over previous devices of a similar nature and is a particular object of the present invention.

Another object of my invention is to provide a perforating device of the type indicated having cam means for actuating the gripping members.

Another object is to provide, in a device of the character specified, a novel form of perforating element which functions to pierce the well casing and to bend or extrude the metal adjacent a side of the pierced hole outwardly to form a louver which serves to prevent stones or the like

from entering the casing through the perforation or from wedging in the perforation to impair the flow of the water or oil into the casing.

A further object is to provide a perforating device which is of relatively simple construction and one which is highly efficient in performing its intended function.

Further objects of my invention will appear from the following detailed description and from the drawings, which are intended for the purpose of illustration only, and in which:

Fig. 1 is a vertical section through a drilled well, showing my improved perforating device as applied to use in perforating the casing of the well;

Fig. 2 is a side view of the device showing it located in a well casing, which is shown in section, and illustrating the gripping members in inoperative position;

Fig. 3 is a view similar to Fig. 2 but showing the gripping members as operative to lock the device in a selected position within the well casing;

Fig. 4 is a longitudinal sectional view through the device, taken on line 4—4 of Fig. 2, showing the perforating means in inoperative position;

Fig. 5 is a fragmentary sectional view of the lower portion of the device, showing the perforating means in its operative position;

Fig. 6 is an enlarged fragmentary view of a portion of one of the perforating members illustrating the manner in which its cutter pierces the wall of the casing;

Fig. 7 is a perspective view of one type of perforator or cutter adapted for use in the device;

Fig. 8 is a perspective view of a portion of a well casing, showing a louver type perforation therein made by the cutter illustrated in Fig. 6;

Fig. 9 is a perspective view of a perforating element or cutter of modified construction; and

Fig. 10 is a perspective view of a portion of a well casing showing the type of perforation or slit formed therein by the cutter illustrated in Fig. 9.

Referring to the drawings in detail, my improved perforating device is shown therein as applied to use in perforating the circular wall of a well casing 15 adjacent the lower end of the casing. While the well may be of a type for obtaining various fluids from the earth, the present device will be described in connection with a well for obtaining water from the earth, by way of example. The lower end of the well casing 15 is located in the water-bearing strata 16 while the upper end of the casing projects slightly above the surface 17 of the ground. As is well known to those versed in the art of deep well drilling, it is necessary to perforate the casing 15 adjacent its lower end to permit the water to enter the casing, the water then being drawn upwardly by suitable pumping means.

My improved perforating device 20 is adapted to perforate the casing 15 at any desired locations and is constructed as next described. The device includes, essentially, an elongate body member 21 which has an axial bore 22, a pair of diametrically opposite rectangular openings 23 (Fig. 4) and a pair of diametrically opposed slots 24 (Fig. 3), the openings and slots being arranged at right angles to each other. The body member 21 has lugs 25 at its upper end between which the lower end of a hydraulic actuating cylinder 26 is welded or otherwise secured. The cylinder 26 has an end plate or cap 27 at its upper end, the cap being provided with a threaded

port 28 into which is screwed the lower end of a hydraulic pipe section 29. To the upper threaded end of the pipe section 29 additional pipe sections may be joined to provide a relatively long hydraulic line 30, which is formed as the device 20 is lowered into the well casing 15. By this means, the perforating device is supported entirely by the line 30, which is relatively rigid, and the device is gradually lowered to a point adjacent the lower end of the well casing 15 by the addition of pipe sections. The upper end of the hydraulic line 30 is, of course, held by suitable hoisting equipment, not herein shown.

Slidable within the hydraulic cylinder 26 is a piston 32 which has a rod 33, the lower end of which is joined to the upper end of a slide member 34 which is slidable in the bore 22 of the body member 21. Adjacent its lower end, the member 34 has a transverse opening 35 and apertures 36 extending at right angles to the plane of the opening. The lower end of the slide member 34 is screw threaded to adapt it to receive stop nuts 37 which are adjustably screwed thereon and adapted to engage the lower end of the body member 21 to limit the upward sliding movement of the slide member.

A second hydraulic line 40 is disposed within the first line 30 and may be composed of pipe sections 40a which are coupled together as the perforating device is lowered into the well casing 15. The upper end of the line 40 projects from the line 30 as indicated at 41 in Fig. 1, while its lower end has an elbow section 42 connected to the lowermost of the pipe sections 40a by means of a coupling 40b. The elbow section 42 projects laterally from the pipe section 29 (Fig. 2), the upper and lower points of exit of the line 40 from the line 30 being sealed to prevent loss of hydraulic fluid from the line 30. Connected between the elbow section 42 and a boss 43 on the lower end of the cylinder 26 is a hydraulic line 44, the boss having a port 45 therein communicating with the interior of the lower end of the cylinder (Fig. 4). It is thus seen that the line 44 constitutes a by-pass and is used for the purpose of introducing fluid under pressure into the lower end of the cylinder 26 to cause the device to perform a perforating operation in the manner to be later explained. The upper end of the pressure line 40 may be connected to a suitable pump, while the upper end of the line 30 may be connected to a reservoir, these parts not being herein shown. A valve 46 is preferably provided in the line 40 to control the introduction of hydraulic fluid into the lower end of the cylinder 26. The line 30 contains a column or head of the hydraulic fluid so that when the valve 46 is operated in a manner to permit flow of the fluid from the bottom of the cylinder 26, this head of fluid exerts sufficient force against the upper end of the piston 32 to force the latter downwardly.

Slidable on the pipe line section 29 immediately above the end cap 27 is an annulus 47 which carries pins 48. Pivoted on the pins 48 are the upper ends of a pair of links 49, to the lower ends of which are pivoted on pins 49' the upper ends of gripping members 50. The members 50 are disposed in the slots 24 and adapted to slide radially therein. The gripping members 50 each have upper and lower inclined cam faces 51 and 52 on their inner sides for a purpose to be presently explained. A cable 53 extends from above the surface 17 of the ground through the casing 15 alongside the line 30 and has its lower end

fastened to the annulus 47 by a connector element 54.

The gripping members 50 are suspended by the cable 53 through the medium of the annulus 47, and are adapted to be moved vertically and reciprocally in response to vertical movement of the cable which is controlled above the surface 17. By permitting the gripping members 50 to be lowered with respect to the body member 21 the gripping members are guided by the slots 24, and as the lowering progresses the members are adapted to be moved radially outward in response to a cam or wedge action between the members and the body member 21. Such motion is imparted to the gripping members 50 by slidable engagement of the cam faces 51 and 52 with corresponding cam faces 55 and 56 which are provided by the body member 21. The limit of downward movement of the gripping members 50 is reached when the outer faces of the members contact the inner surface of the casing 15 whereby the body member 21 is wedged into a fixed position within the casing. After the perforating operation, which will hereinafter be described, the body member may be released from its wedged position by exerting a short pull upon the cable 53 which will cause the gripping members to be moved upwardly and radially inward as determined by the cam faces 51, 52, 55 and 56, thereby permitting the perforating device 20 to once again pendulously hang within the casing 15.

Perforating members are provided for perforating the wall of the casing 15, these members consisting in a pair of toggle levers 60 and 61. Each toggle lever includes an upper lever-arm 62 the upper end of which is pivoted on a pin 63 extending across the opening 23 (Fig. 4). Pivotedly connected to the lower end of each lever-arm 62, by means of a pin 64, is a lower lever-arm 65, the two lever-arms 65 being pivotally connected within the opening 35 of the slide member 34 by a pin 66 whose opposite ends are retained in the opposite apertures 36. The apertures 36 are illustrated in the form of vertical slots to provide limited lost motion between the pin 66 and the slide member 34. However, in certain devices it may be preferable to maintain the pin 66 and the slide member 34 rigid, and accordingly the apertures 36 would take the form of circular holes. The upper lever-arms 62 carry perforating elements or cutters 70 which may be of the type shown in Figs. 2 to 7. Each cutter 70 consists of a vertical rectangular plate 71 adapted to be set into a recess 72 in the edge of a lever-arm 62 and to be held in place therein by means of screws 73. Each plate 71 is provided with a piercing element or cutter 75 which projects laterally therefrom and formed with an arcuate cutting edge 76. The upper surface of each cutter 75 curves upwardly from the cutting edge 76 so that the cutter has a wedge-shaped cross section (Fig. 6), the upper surface providing a cam face 77.

When the piston 32 and slide member 34 are forced upwardly in response to hydraulic fluid introduced into the lower end of the cylinder 26, the slide member acts to move the pin 66 upwardly, thereby causing pivotal movement of the lever-arms 62 and 65 from the position shown in Fig. 4 to that illustrated in Fig. 5. The cutters 70 are thus forced radially outward and their cutting edges 76 pierce the casing wall as shown in Fig. 6. By this means, holes or perforations 80 are made in the well casing 15 and it will be

noted that the upper cam portions 77 of the cutters act to bend or flare the metal adjacent the upper edge of the perforation outwardly and upwardly to provide louvers 81 which overlie the perforation so as to guard against the entrance of pieces of rock into the casing.

It is particularly noted, during the perforating operation, that were it not for the presence of the gripping members 50 intermediate the body member 21 and the casing 15, the cross-section of the casing would tend to become oblong due to the lateral force component exerted by the cutters 70. By use of the gripping members, the perforation may be made without impairing the strength or altering the form of the casing, for any tendency for the casing to reduce any chordal or diametrical dimension is opposed by the wedged body member 21 and the gripping members 50. Further, by the cooperation of the gripping members with the body member 21, the device is maintained centermost of the well during each perforating operation. In such a manner, the locations of the perforations are known to be diametrically opposed and their location may be indexed at the ground surface. Accordingly, additional perforations may be made at the same well elevation, but angularly disposed from perforations previously made, and accurately located so as to preclude overlap of perforations that would tend to shear the casing.

The invention also contemplates the use of perforators or cutters 83 of the alternative type disclosed in Fig. 9. Such cutters may each include a plate portion 84 adapted to be secured to the lever-arms 62, and a relatively long vertical knife 85 having a point 86 at its lower end. When the lever-arm 62 is pivoted outwardly, the point 86 pierces the wall of the casing 15 and continued movement of the cutters 83 causes their knives 85 to slice through the metal to form vertical slits 87 as shown in Fig. 10.

Assuming that it is desirable to perforate the well casing 15 adjacent its lower end and that it is preferable to provide two vertically-spaced series of ten perforations, the perforating device 20 is lowered in the casing in the manner next explained. To lower the device 20, pipe sections 29 and 40a are added to those already attached to the actuating cylinder 26 and following the addition of each section, the device is lowered further into the well casing 15. At the same time, the cable 53 is paid out from the winch or other wind-up device. Eventually, the perforating device 20 is located adjacent the lower end of the well casing 15 and the upper projecting ends of the hydraulic lines 30 and 40 are connected respectively to the reservoir and pump, not shown, and the perforating device is ready for operation.

To perform a perforating operation, that is, to provide a pair of diametrically opposite perforations in the wall of the casing, the operator first releases any tension that may be exerted on the cable 53, preferably by first raising the cable to its upper limit as determined by the upward travel of the annulus 47 about the pipe section 29 and then releasing the cable to permit the gripping members 50 to drop into position. As the gripping members move downwardly, their cam faces 51 and 52 act against the cam faces 55 and 56 to cause the members to move radially outward and into wedged engagement with the wall of the casing 15. Then the operator merely opens the selector valve 46 to cause hydraulic fluid to be forced down through the line 40 and into the lower end of the cylinder 26 to forcibly

raise the piston 32 and thus slide the slide member 34 upwardly. As the slide member moves upwardly, the pin 66 is also caused to be moved upwardly so that the toggle levers 60 and 61 are pivoted from the position shown in Fig. 4 to that illustrated in Fig. 5. In this manner, the perforators or cutters 70, or 83, are forced outwardly so that they pierce the casing wall as shown in Figs. 5 and 6 to provide a pair of perforations or openings 80 or 87, as the case may be.

During the perforating operation, the hydraulic fluid within the upper end of the actuating cylinder 26 is displaced and forced upwardly into the line 30 which, as previously explained, contains a column or head of the fluid. The amount of hydraulic fluid displaced from the upper end of the line 30 or the change in level of the fluid within this line provides an indication of the amplitude of movement of the slide member 34 so that the operator can readily determine whether the cutters have completely penetrated the wall of the casing 15. Following the perforating operation, the valve 46 is operated in a manner to permit egress of the hydraulic fluid from the lower end of the cylinder 26 and at this juncture the head of fluid within the line 30 exerts sufficient downward force to return the slide member 34 to first position and move the perforating members to inoperative position. The return of the gripping members 50 to first position may be facilitated by exerting an upward pull on the cable 53 to free the wedge-shaped cam faces of the members and the body member.

After the first pair of perforations has been made, the entire perforating device 20 is indexed to a new position by merely rotating the rigid lines 30 and 40. By providing index marks at the upper end of the casing 15 and on the line 30, the degree of rotation of the line 30 and perforating device 20 can be readily determined. When ten perforations are being made at one level, the device is indexed through an angle of 36° between each perforating operation to complete the series of perforations.

Following the completion of one group of ten perforations, the entire perforating device 20 is raised within the casing 15 to a new level by drawing the cable 53 and the lines 30 and 40 upwardly. The amount of upward movement of the device can be readily ascertained by measuring the length of the projecting end of the line 30 so that the perforating device 20 can be accurately located in its new position. After the device 20 has been disposed at the higher level within the casing 15, the device is operated in the sequence explained above to make a new series of perforations.

After the well casing 15 has been perforated in the foregoing manner, the device 20 is withdrawn from the casing by merely drawing the cable 53 and the line 30 upwardly by any suitable equipment and, during this operation, the uppermost tubes or pipe sections of the lines 30 and 40 are uncoupled in the manner well known to those versed in the art.

While I have herein shown and described the improved perforating device as embodied in a preferred form of construction, by way of example, it will be apparent that various changes might be made in the structure and in the manner of applying the device to use, within the spirit of the invention. Consequently I do not wish to be limited in this respect, but desire to be afforded the full scope of the appended claims.

I claim as my invention:

1. A device for perforating a well casing or the like, including: a body member adapted to be lowered into the casing and having at least two radial openings therein and provided with cam surfaces; a perforating member supported by said body member; a slide member slidable vertically in said body member and operatively connected to said perforating member to cause movement thereof to perforate said casing; fluid actuated means for sliding said slide member; a freely suspended gripping member slidable radially in each of said openings and adapted to engage the interior of the wall of the casing, each gripping member having at least one cam surface engageable by one of said cam surfaces of said body member during vertical sliding movement of said gripping member so that each gripping member is slid radially outward into engagement with said casing wall to retain the device in selected positions in the casing; a holder slidable longitudinally of said body member and suspended from a cable lowered into the casing; and links connected between said holder and the upper ends of said gripping members for suspending said gripping members in said openings.

2. A device for perforating a well casing or the like, comprising: a body member adapted to be lowered into the casing and having at least one radial opening therein; a cam surface for said body member; a freely suspended gripping member for said opening and movable vertically relative to said body member and slidable radially outward in said opening and adapted to engage the interior of the wall of said casing, said gripping member having at least one cam surface engageable by said cam surface of said body member during vertical sliding movement of said gripping member to cause said radial movement; a holder slidable longitudinally of said body member and suspended from a cable lowered into the casing; a link connected between said holder and the upper end of said gripping member for suspending said gripping member in said opening; at least one lever-arm pivoted to said body member and provided with a perforating cutter adapted, when said lever-arm is pivoted outwardly, to pierce the wall of the casing; a slide member slidable vertically in said body member and connected with said lever-arm so that relative sliding movement between said slide member and said body member in one direction causes said lever-arm to pivot radially outward; and fluid actuated means for sliding said slide member.

3. A device for perforating a well casing or the like, comprising: a body member adapted to be lowered into the casing; a cam surface for said body member; a gripping member adapted to engage the wall of said casing and suspended adjacent to and movable vertically and laterally relative to said body member, said gripping member having a cam surface engageable by said cam surface of said body member during relative vertical movement of said gripping member to cause said lateral movement; a holder movable longitudinally of said body member suspended in said casing; means connecting said holder and said gripping member suspending said gripping member adjacent said body member; a perforating member supported by said body member; a slide member slidable relative to said body member and operatively connected to said perforating member to cause movement thereof to perforate said casing; and means for moving said slide member.

4. A device for perforating a well casing or the like, comprising: a body member adapted to be lowered into the casing; a plurality of cam surfaces for said body member; a plurality of gripping members adapted to engage the wall of said casing and each being suspended adjacent to and movable vertically and laterally relative to said body member, each of said gripping members having a cam surface engageable by one of said cam surfaces of said body member during relative vertical movement of said gripping member to cause said lateral movement; a holder movable longitudinally of said body member suspended in said casing; suspension means connecting said holder and said gripping members to position said gripping members relative to said body member; a lever-arm supported by said body member and provided with a perforating cutter adapted, when said lever-arm is moved toward said casing, to pierce the wall of said casing; a slide member movable relative to said body member and operatively associated with said lever-arm so that relative movement between said slide member and said body member in one direction causes said lever-arm to move toward said wall; and means for moving said slide member.

5. A device for perforating a well casing or the like, including: a body member adapted to be lowered into the casing and having an opening therein and provided with a cam surface; a first lever-arm supported by said body member; a slide member movable relative to said body member; a second lever-arm connected to said slide member and said first lever-arm so that relative movement between said slide member and said body member in one direction causes one of said lever-arms to move toward the wall of said casing; a perforating cutter for one of said lever-arms adapted, when said last-mentioned lever-arm is moved toward said wall, to pierce said wall; means for moving said slide member; and a suspended gripping member vertically and laterally movable in said body member opening and adapted to engage the interior of said wall, said gripping member having a cam surface engageable by said cam surface of said body member during vertical movement of said gripping member to cause said lateral movement.

6. A device for perforating a well casing or the like, comprising: a body member adapted to be lowered into the casing and having at least one opening therein; a cam portion for said body member; a suspended gripping member for each said opening and movable vertically relative to said body member and slidable outward in said opening and adapted to engage the interior wall of said casing; a cam surface for each of said gripping members for engagement with the cam portion of said body member during vertical movement of said gripping members to cause their outward movement to retain the device in selected positions in the casing; suspension means for said gripping member slidable longitudinally of said body member and suspended within said casing; means connecting said suspension means and said gripping members for suspending each gripping member in its body member opening; a first lever-arm pivotally connected to said body member; a slide member movable relative to said body member; a second lever-arm pivotally connected to said slide member and said first lever-arm so that relative movement of said slide member and said body member causes one of said lever-arms to move toward the wall of the said casing; a perforating cutter for said lever-arm

11

so moved adapted, when said last-mentioned lever-arm is moved toward said wall, to pierce said wall; and fluid actuating means for moving said slide member.
